UNITED STATES PATENT OFFICE.

GEORGE MURRAY, JR., OF CAMBRIDGEPORT, ASSIGNOR OF ONE-HALF TO
CHARLOTTE MORGAN, OF MELROSE, MASSACHUSETTS.

GEARING.

SPECIFICATION forming part of Letters Patent No. 286,550, dated October 9, 1883.

Application filed March 17, 1883. (No model.)

To all whom it may concern:

Be it known that I, GEORGE MURRAY, Jr., a citizen of the United States, residing at Cambridgeport, in the county of Middlesex and State of Massachusetts, have invented certain new and useful Improvements in Gearing; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a front view of my gearing. Figs. 2 and 3 are sectional views. Fig. 4 is a face view, and Fig. 5 is a perspective section.

This invention has relation to devices for 20 converting reciprocating motion into rotary motion; and it consists in providing, in connection with the main shaft, a worm-wheel, and in connection with the reciprocating cross-head, intermittently-rotating screws, having 25 automatic stop devices, all as hereinafter set forth.

In the accompanying drawings, the letter *a* designates the main shaft, and *b* a piston-rod reciprocating in the direction of its length.

30 To the rod *b* is secured a cross-head, *c*.

On the main shaft is keyed a worm-wheel, *D*, and to the cross-head are connected the screws *A* and *B*, which extend parallel to each other and to the rod *b* on each side of the 35 worm-wheel *D*, which they engage. The screws *A* and *B* are designed to reciprocate with the cross-head, and are provided with suitable guides, as at *E*. The screw *A* is formed with a head, *g*, having a rounded bearing-surface, *h*, on its outer side, and is provided with the annularly-grooved pivot-extension *k*. It 40 is seated in a recess, *L*, of circular form, made in the top or face of the cross-head. The recess *L* is provided with an internal ratchet, *m*, and below the same with a circular groove or bearing, *n*, for a circular spring, *s*, to which is fastened, or on which is formed, a lug or projection, *p*, which extends upward or opposite the teeth of the circular ratchet *m*.

To the head *g* of the screw *A* is pivoted a 50 dog, *V*, having a notch, *r*, in the outer edge of its body, in which is received the lug or projection *p* of the friction-spring *s*. It is apparent that when the screw *A* is turned in one direction the friction ring or spring *s* will 55 cause the dog to engage the ratchet, and that when this screw is turned in the opposite direction the friction-spring will cause a slight vibration of the dog on its pivot, immediately releasing said dog from the ratchet and holding it away from the same during the rotation of the screw in this direction. This screw is held to the cross-head by means of an internally-flanged screw-plug, *t*, which is screwed into the threaded aperture *w* in the bottom of 60 the recess *L*, and is held from turning by a set-screw, *v*. An oil-cup, *C*, is connected to the projecting rim of the aperture *w*. The base of the recess *L* around the aperture *w* is rounded in concave form to correspond with the rounded 65 convex bearing-surface *h* of the head of the screw, for which it forms a seat, as indicated at *l*. The screw *A* is designed to turn freely 70 on its small bearing in the hollow plug *t* when the cross-head moves in one direction, and to 75 be rigidly fixed in position, bearing against the broad concave seat *l* when it is at work, the cross-head moving in the opposite direction.

The screw *B* is formed with a head, *g'*, having a rounded bearing-surface, *h'*, on its upper or inner side, and is provided with a pivot-extension, *k'*. The head *g'* is seated in a recess, *L'*, which is formed in the back of the cross-head *c* at the opposite end thereof from 80 the recess *L*. The screw *B* is passed through the aperture *e*, formed in the center of the recess, and the rounded bearing-surface *h'* is designed to engage a concave seat, *l'*, in said recess, as shown in the drawings. Across the 85 mouth of the recess *L'* extends a bar or bearing, *d*, which is threaded centrally to receive the screw-bearing *G*, against which the pivot-extension *k'* of the screw *B* is designed to bear when the screw is in rotation.

To the head of the screw *B* is pivoted a dog, *V'*, having a notch, *r'*, in the outer edge of its body, in which is received a projection, *p'*, of

2 a friction-spring, s' , which is seated in an annular recess or bearing, n' , in the circular wall of the recess L' , which is also provided with an internal ratchet, m' , below said groove. 5 When the screw B is turned in one direction, the friction ring or spring s' will cause the dog to engage the ratchet m' , and said spring will effect a disengagement of the dog when the screw is turned in the opposite direction.

10 It is apparent that when the cross-head c is moved by the reciprocating rod or connection b toward the worm-wheel it will push against the ends of the screws A and B, which are connected thereto, and that when the cross-head 15 is moving in the opposite direction it will pull the screws A and B with it in its movement. The pushing action of the cross-head with reference to the screw A will at once bring its broad convex bearing h against the seat l , and 20 by the engagement of its thread with the worm-wheel a tendency to rotate will be effected, which, through the operation of the friction spring or ring s , will throw the dog V into engagement with the ratchet. In this 25 manner the screw A will become fixed, so that it cannot rotate, and it will act as a rack, turning the worm-wheel and its shaft, as indicated by the arrow in the drawings. At the same 30 time the cross-head will engage the screw B by the small bearing-screw G , and said screw B will be rotated freely by the action of the worm-wheel, its dog V' being disengaged from the ratchet m' by the operation of the friction-ring s' . On the return of the cross-head in moving 35 away from the worm-wheel the latter will tend to reverse the rotary movement of the screw B, putting its dog into engagement with the ratchet m' , so that its position becomes fixed, and it operates as a rack, turning the worm-wheel,

as before in the direction of the arrow. At 40 the same time the broad bearing h of the head of the screw B is brought into engagement with the concave seat in the recess L of the cross-head, and the screw A, being now impelled by the worm-wheel to turn in the opposite direction, effects through the operation of its friction-ring s the release of its dog V , which is held out of engagement, so that said screw A rotates freely on the small bearing t . By the repeated reciprocating movements of 45 the cross-head the screws engaging the worm-wheel are alternately held and released, so that each in succession operates as a rack, one for the forward movement and the other for the reverse movement, and the worm-wheel and 50 its connected shaft are continuously turned in the same direction.

Having described this invention, what I claim and desire to secure by Letters Patent is—

1. A device for converting motion, consisting of a worm-wheel on the main shaft, in connection with intermittently-rotating screws, in connection with a reciprocating cross-head, and having automatic stop devices, substantially as specified. 65

2. In a device for converting motion, a worm-wheel between engaging-screws pivoted to a cross-head and carrying dogs, in combination with ratchets of the cross-head and friction devices, operating alternately to release and 70 set the dogs, substantially as specified. 75

In testimony whereof I affix my signature in presence of two witnesses.

GEORGE MURRAY, JR.
